(57) **CLAIM**

The ornamental design for a compact air purifier, as shown and described.

DESCRIPTION

FIG. 1 is a front right perspective view of the compact air purifier of the present invention;

FIG. 2 is a rear right perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof; and,

FIG. 8 is a left side elevation view thereof.

The broken line showing of parts of the drawings is included for the purpose of illustrating use and environment and forms no part of the claimed design.
